ELEVATOR APPARATUS

Martin B. McLaughlin, Malden, Mass.

Application May 14, 1932, Serial No. 611,299

4. Claims. (Cl. 187—17)

My invention is an elevator apparatus and may be embodied in a dumbwaiter. It has for its object to improve the construction and operation of elevator apparatus.

The advantages of the hydraulic dumbwaiter for many situations are generally acknowledged but its use has been restricted on account of the cost of installation. The only well developed type of hydraulic dumbwaiter heretofore proposed was the direct plunger type wherein the car was mounted upon the upper end of a plunger whose lower end portion was housed within a well or cylinder. Dumbwaiter apparatus of this type is comparatively expensive to install and to operate.

Another objection to hydraulic dumbwaiter apparatus has been the liability of leakage of water and the messiness and damage resulting therefrom.

At the present time there is a demand for a simple, labor-saving, fool-proof and economical, power-operated dumbwaiter for lunch rooms, soda fountains, restaurants, markets and other stores, etc., particularly of the under-counter type, for service between two floors of a building as, for example, between the basement and street floor.

The principal object of my invention is to provide an inexpensive, reliable, and efficient hydraulic dumbwaiter apparatus whose construction will obviate the objections above noted and which will be particularly adapted for use in situations such as those just referred to.

To this end I have developed and constructed a hydraulic dumbwaiter apparatus including a novel compact hydraulic engine that is preferably made as a unit adapted to be fixed in position adjoining the shaftway or elevator well, either horizontally or vertically, in an out-of-the-way position where it occupies little or no floor space.

In the best form of my invention this engine is connected by a system of conduits with a supply of water under head or pressure and also with an offtake or drain, semi-automatic valve means being provided for controlling communication between said engine and said supply and offtake and through which the movements of the car of the apparatus are controlled.

It is also a feature of my invention in its best form that the hydraulic pressure of the water service of the building within which the apparatus is installed is utilized as the source of power.

Another feature of my invention is that the system of conduits referred to includes a supply

conduit leading from the water service of the building to said valve means in which supply conduit is provided a check valve that closes toward said water service. At a point between said check valve and said valve means is connected one end of an auxiliary supply conduit which extends to the bottom of an accumulator tank from which a second supply of water under head or pressure is available for use at times in operating the engine.

Other features of my invention are hereinafter pointed out.

In the accompanying drawings:

Figure 1 is a vertical sectional view of a portion of a building equipped with a hydraulic dumbwaiter apparatus constructed in accordance with my invention.

Figure 2 is a side elevation, partly in section, of the upper portion of the hydraulic engine unit forming part of the apparatus illustrated in Fig. 1.

Figure 3 is a side elevation, partly in section, of the lower portion of said unit.

Figure 4 is a front elevation of the portion of the hydraulic engine unit illustrated in Fig. 2.

Figure 5 is a front elevation of the portion of the hydraulic engine unit illustrated in Fig. 3.

Figure 6 is a central longitudinal sectional view of the three-way operating valve, hereinafter described.

Figure 7 illustrates an alternative form of valve operating mechanism.

The embodiment of my invention herein illustrated includes a hydraulic engine unit that is indicated generally in Fig. 1 at 10, and this unit comprises an elongate bed or bar 11 with which the other parts of the engine may be permanently connected and by means of which the engine is fastened to its supporting fixture.

In Fig. 1 the elevator apparatus is illustrated as provided within a building for service between two floors of the latter and when the elevator apparatus is thus installed within a building the bar 11 may be fixed at its opposite ends to the frame of said building as shown.

It is a feature of the present invention that the bar 11 is a length of channel iron upon the inner side or face of the web of which is fastened, as by screws 12, a bracket comprising a cylinder head 13 that is the lower or intermediate portion of a yoke whose arms 14 are secured by screws 12 to the web of the channel bar 11. The cylinder head 13 is formed with a cylindrical threaded recess into which is screwed the upper exteriorly 55

threaded end of a cylinder 16 consisting of a length of tubing, preferably brass.

At its lower end the cylinder 16 is telescopically and firmly fitted into a socket provided at the upper end of a yoke cylinder head 17 having a pair of integral legs 18 fastened by bolts 19 to the inner face of the web of the channel bar 11. The head 17 comprises two concentric circular walls 20 and 21 which provide between them an annular trap chamber 22 communicating at its upper end with the interior of cylinder 16 and which is closed at its lower end by a bottom wall 23.

Within the cylinder 16 is a piston head 24 that is fixed rigidly to the upper end of a tubular piston rod 25 which extends downwardly through the central aperture of the cylinder trap head 17 to the exterior of the latter. Fixed to the lower end of the tubular piston rod 25 is a sheave-carrying yoke 26 including an intermediate hub portion 27 fast on piston rod 25 and a pair of depending arms or side frames 28, Fig. 5, by which the axle 29 of a sheave 30 is supported in a position parallel with the web of the channel bar 11.

The depending arms 28 of yoke 26 also support the axle 31 of a truck 32 which bears against the inner side or face of the web of the channel bar 11 and is adapted to roll thereon thus providing lateral support for the free end of the piston rod, particularly when the latter is near the limit of its outward movement. The outer sides of the depending arms 28 of the yoke 26 fits snugly against the inner faces of the flanges of the channel bar 11 but are free to move longitudinally relatively thereto.

Above the sheave 30 the yoke 26 is provided with a cross bar 33 to which may be fastened one end of a wire cable 34.

Between the upwardly extending arms 14 of the head 13 is arranged a sheave 35 that is rotatably supported by an axle 36 mounted at its opposite ends in the arms 14 of the yoke.

The wire cable 34 extends from the bar 33 of yoke 26, Fig. 3, to and over the sheave 35, Fig. 2, thence downwardly to and around the sheave 30, Fig. 3. From the sheave 30, cable 34 extends upwardly within the channel bar 11, through the floor F of the building, to and around guide sheaves 36 and 37, and thence downwardly to the car 38 of the apparatus to which its other end is fastened.

The car 38 is movable vertically within a shaft-way or well 39 at opposite sides of which are provided rails 40 by which the car is guided as it is moved vertically.

The sheaves 36 and 37 are mounted upon a crossbar or framework 41 provided at the tops of the rails 40.

Sometimes two sheaves are mounted on axle 29 in which case the end of cable 34, instead of being fastened to cross-bar 33, is carried around the second or added pulley and fastened at its end to an eye 84 provided on the lower head 17. This arrangement would give a four to one ratio between the movement of yoke 26 and the movement of the car. The construction illustrated which employs a single sheave 30 gives a three to one ratio.

The upper head 13 of the cylinder is formed with a cored port 42, one end of which communicates with the upper end of cylinder 16 and the opposite end of which is connected by a pipe 43 with a port 44 provided in the body 45 of a three-way valve that is indicated generally at 46. Figs. 2, 4 and 6. The body 45 of this three-way valve 75 may be embraced by a clamp 47 by means of

which it is fastened rigidly to the cylinder 16.

The body 45 is made with an inlet port 48, Fig. 6, that is connected by a conduit with a pipe 49 that is part of the water service system of the building within which the elevator apparatus is arranged. This conduit includes pipes 50, 51 and 52 and also a check valve 53 which closes toward the service pipe 49. I herein provide an accumulator tank 54 which may be entirely closed and air tight except for a port at its bottom connected by a pipe 55 with the conduit 50—51—52—53 at a point between check valve 53 and three-way valve 46. The tank 54 is incorporated in the apparatus in an empty condition, except for air, and when a supply of water from the water service pipe 49 is available, it will rise through the pipe 52, check valve 53, and pipes 51 and 55 into the accumulator tank 54, and the air that is within the latter may be compressed by the water that forces its way into said tank. 20

When the tank 54 is air tight the air under compression therein supplies water to the engine under pressure sufficient to operate the latter. When said tank 54 is not a closed air tight tank then it will be located in an elevated position 25 within the range of the head of the water service system but at sufficient height to supply water to the engine under enough head to operate the engine.

Fixed within the body 45 of the three-way 30 valve 46 is a tubular lining or bushing 56 within which is arranged a valve member that is indicated generally at 57. At its upper end this valve member is pivotally connected to the lower end of a link 58 whose upper end is pivotally connected 35 with one arm of a lever 59, Fig. 4, that is fulcrumed at 60 upon an arm 61 forming part of the head 13. The other arm of lever 59 is pivotally connected at 62 to a vertically disposed shipper rod 63 that is slidably mounted adjacent 40 to its lower end in a bearing provided in an arm 64 projecting from the channel bar 11.

As herein shown the shipper rod 63 is moved endwise manually to adjust the valve member 57 to start the movement of piston 24 in one direction or the other, and as the piston nears the limit of its movement in that direction, an arm 65 forming part of the yoke 26 engages either the collar 66 or the collar 76 which acts through rod 63, lever 59 and link 58, to return valve member 57 to its intermediate position thereby interrupting the passage of water to and from the cylinder 17 and stopping movement of piston 24. 45

The outer end portion of this arm 65 is formed with a vertical hole that is loosely occupied by 55 the shipper rod 63, and as the piston nears the limit of its downward movement said arm engages the collar 66 fast on shipper rod 63 and moves the latter downwardly until the valve element 57 reaches its intermediate position and 60 shuts off the supply of water to the cylinder.

When the piston 24 is to be driven upwardly the shipper rod 63 is manually depressed or lowered beyond the position to which it was moved by the arm 65 which adjusts the valve member 65 57 from its intermediate position into a position where the upper end of the cylinder 16 is connected with an offtake conduit including a pipe 67. This pipe 67 has its upper end connected with the lower end of the body 45 of the three-way valve while its lower end is connected with the drain pipe 68 of the building. 70

When the upper end of the cylinder 16 is thus connected with the offtake pipe 67, the weight of the car 38 carries the latter downwardly and it 75

acts through the cable 34 to raise the piston 24. This downward movement of the car is regulated and controlled by the water that is displaced from the upper end of cylinder 16 by the upward movement of the piston 24.

Near its lower end the body 45 of the three-way valve is made with an annular chamber 69 surrounding the tubular bushing 56, the latter being made with radial ports 70 extending from the interior of bushing 56 to said annular chamber 69.

Just above the annular chamber 69, the body 45 of the three-way valve is also formed with another annular chamber 74 surrounding the bushing 56 through which said bushing 56 extends, and within this chamber 74 the said bushing is made with radial ports 75 which always connect the portion of the interior of bushing 56 which is between the valve pistons 71 and 72 with the annular chamber 74. This annular chamber 74 communicates with one end of the supply pipe section 50 so that the chamber 74 is continuously in communication with the water supply pipe 51 and is filled with water under substantially the same head or pressure which exists within water service pipe 49, or accumulator tank 54.

The valve member 57 is constructed with three valve pistons 71, 72 and 73, and the valve piston 71 always occupies a position above the ports 75 while the valve piston 72 always occupies a position below the ports 75. Therefore, the pressure effects of the water that is within the bushing 56 that are imposed upon the valve pistons 71 and 72 are balanced, said two valve pistons being of the same area.

The intermediate valve piston 72 co-operates with the lower valve piston 73 to control the ports 70. In Fig. 6 these two pistons are disposed one at each side of said ports 70 so that communication between the lower end of the "to and from" pipe 43 and offtake pipe 67 is shut off as is also communication between the lower end of pipe 43 and the supply pipe section 50. With the valve member 57 occupying the position shown the power piston 24 of the engine is at rest and this is the condition of the valve member while the power piston 24 remains at the limit of its stroke in either direction, or stationed at any intermediate position.

When the shipper rod 63, Fig. 4, is manually shoved downwardly to start the power piston 24 upon its upward stroke it acts through the lever 59 to raise the valve member 57 until the piston 73 is above the ports 70, Fig. 6. When said valve piston occupies this position communication exists between the lower end of the to and from pipe 43 and the offtake pipe 67 so that as the piston 24 is raised by the weight of the car, the water above said piston is discharged from cylinder 16 through pipe 43 into the annular chamber 69 from which it passes through ports 70 and thence downwardly through the offtake pipe 67.

As the power piston 24 nears the limit of its upward movement its arm 65, Fig. 3, engages the collar 16 fast on shipper rod 63 and raises the latter. As the shipper rod 63 is thus lifted, it acts through the lever 59 to lower the valve element 57 until it occupies its intermediate position shown in Fig. 6 which stops further movement of the power piston.

The power piston 24 is started upon its downward travel by manually raising the shipper rod 63 which acts through lever 59 to lower the valve member 57 to a point where the valve piston 72 is

below the ports 70 of the bushing 56. This establishes communication between the pipe 43 and supply pipe section 50 via the interior of bushing 56 and the annular chamber 74. Water under pressure then flows from supply pipe section 50 through the valve body 45, pipe 43 and the cored port 42, Fig. 2, into the cylinder 16 at the upper end thereof.

As the power piston 24 nears the limit of its downward movement it is automatically stopped as above described by the engagement of arm 65 with collar 16. In this way the control of the apparatus is semi-automatic, the power piston being manually started upon its travel in either direction and automatically stopped when it reaches the limit of its movement in that direction.

The interior of the cylinder 16 that is below the power piston 24 is always in communication with the interior of the tubular piston rod 25 through ports 77 provided in said piston rod near the upper end thereof, while the interior of the lower end portion of the piston rod 25 always communicates with the outside atmosphere through ports 78 formed in said piston rod near the lower end thereof. It will thus be clear that the air that is within cylinder 16 below power piston 24 is free to pass into and out of said cylinder without retarding materially the movements of said piston and this is a feature of this invention.

It is also a desirable feature of this invention that the ports 77 are disposed near the power piston 24 so that they are within the cylinder 16 when said power piston is at the limit of its downward movement, and it is also a novel feature of this invention that the ports 78 are disposed near the lower end of the tubular piston rod 25 so that they are always outside of the lower cylinder head 17. Thus the portion of the interior of cylinder 16 below the power piston 24 is open to the outside atmosphere at all times and is freely vented.

It will be clear to those skilled in this art that, if desired, the ports 77 and 78 may be positioned relatively to piston 24 so that just before the latter reaches the limit of its downward movement the said ports 77 enter within the circular wall 20 and are closed thereby providing a cushioning stop for the downward movement of the piston.

The trap chamber 22 is provided at the lower end of cylinder 16 to catch any water that may succeed in leaking past the power piston 24 from the upper end of the cylinder, and said chamber is provided adjacent to its bottom with an outlet that is connected by a drain pipe 79 with offtake pipe 67 and drain pipe 68 of the building. Whatever water tends to accumulate within the trap chambers 22 and 82 flows away by gravity through their outlets and pipes 79 and 83. As a result of this construction it is impossible, when all joints are in good condition, for water to leak out of the apparatus otherwise than via the drain pipe 79.

It will be clear from the above description that when the hydraulic engine 10 is disposed in a vertical position as shown, the weight of the power piston and parts connected therewith serves to counterbalance, in part, the weight of the car 38 and its load.

Also, the apparatus herein illustrated is particularly constructed to utilize the water of the water supply service of a building within which the apparatus is arranged and it is a fact that use of water on the various floors of the building will cause the pressure of the water within the

service pipe 49 to vary considerably. The purpose, therefore, in providing the accumulator tank 54 is to compensate for variations of the water pressure within the lower end of the pipe 55. When the pressure or head within service pipe 49 is below normal the check valve 53 will automatically be maintained closed and the hydraulic engine will be served with water from the accumulator tank 54. When, however, the water pressure within the service pipe 49 is raised or restored to normal through reduction in the use of water in other parts of the building, water will flow upwardly from service pipe 49 past check valve 53 and upwardly through pipe 55 into tank 54 thereby replenishing the supply of water within the latter.

The collar 66 near the lower end of the shipper rod 63 is provided with a handle 80 by means of which said rod may conveniently be operated by a person on the lower floor. At its upper end, and above the floor F, the shipper bar 63 is provided with another handle 81 by means of which a person on the upper floor may conveniently operate said shipper rod.

From the above description it will be seen that I have provided an inexpensive and efficient self-contained portable dumbwaiter apparatus which can be conveniently transferred to and quickly installed in a new or existing building, and it is a feature of this invention that this dumbwaiter apparatus includes a compact, self-contained, hydraulic engine mounted upon a base-bar which is preferably a metal channel bar, said engine being adapted to be installed either in a vertical position close to the shaftway or elevator well where it occupies little space, or horizontally immediately below the ceiling where it will occupy no floor space.

It will also be seen that this hydraulic engine including its operating valve 46, its automatic terminal stop mechanism; and the shipper mechanism, are permanently assembled on the channel bar as a complete self-contained power unit ready for installation which can be connected with the car of an existing manually operated dumbwaiter and with the water service of the building at comparatively small expense.

My new dumbwaiter apparatus is small and convenient in its construction and operation and costs very little to operate and maintain.

The lifting capacity of the above described apparatus is limited to the maximum effort of the water pressure and in case of obstruction to the ascent of the car no breakage of cable or machine will result because of the limited lifting effort applied to the car, and to the obstruction, thus avoiding shut down or serious damage.

In the descent of the car the plunger is "over-hauled" by the weight of the car and load. Should the car be obstructed by misplacement of load, or otherwise, the hoist cables do not slacken or come off of the leading sheaves and the car cannot drop. In case of obstruction the downward effort on the car is less than the weight of car and load as the moving parts of the hydraulic engine serve as a partial counter-weight.

As will be clear the self-contained hydraulic engine unit can be readily installed to operate existing hand operated dumbwaiters. It is calculated that three sizes of engines and two roping ratios at the engine, will meet practically all pressure and load requirements when the apparatus is installed for use in connection with the water service system of a building.

As will be clear to those skilled in this art an electric push button control system may, if desired, be substituted for the above described direct manually operated control mechanism for the three-way valve. It will also be clear that it is not essential that the valve means be embodied in a single three-way valve unit.

Any leakage of water past the lower valve piston 73, Fig. 6, is conducted away through the drain pipe 67, while the upper end of the body 45 of the three-way valve is made with a cup 82 to receive any water which may leak past the upper valve piston 71. As this water collects within the cup 82 it flows by gravity from the latter through pipe 83 and drain pipe 67 to the drain pipe 68 of the drainage system of the building.

It will be clear from the above description that the accumulator tank 54 holds a reserve supply of water under head or pressure which is automatically delivered to the apparatus when the head or pressure of the water within the service pipe 49 falls below normal through excessive use of water in other parts of the building or for other reasons. When this accumulator tank 54 is an open tank, it will be disposed in an elevated position within the range of the head or pressure of the water within service pipe 49 but when the tank 54 is a closed and air tight tank, it may be positioned lower than shown in the accompanying drawings, for example, within the room containing the hydraulic engine.

The control mechanism for valve 46 which includes the vertically movable rod 63 is operable by a person on either floor of the building at any time to start, stop and reverse the direction of movement of the car 38. In particular, when the car is at rest at the end of its movement in either direction, either operator may operate the bar 63 to start the motion of the car in the opposite direction.

In Fig. 7 I have shown a "sending only" control mechanism that is organized and arranged so that when the car is at the limit of its movement in either direction, only the operator on that floor of the building where the car is at rest can operate the valve to start the car on its travel toward the other floor. At the same time this mechanism is so constructed and organized that after the car has been started, and while it is in motion, either operator can stop the car at any point during its travel, and after the car has been thus stopped at an intermediate point either operator may cause the motion of the car to be resumed but only in a direction away from him. Thus the mechanism shown in Fig. 7 is what might be termed a "sending only" control mechanism.

Referring to Fig. 7 the arm 65 on the piston head cooperates with two abutments 86 and 87 provided upon a rod 88 slidably supported by the base member 11. Slidably mounted on the rod 88 is a sleeve 89 to which one arm of the lever 59 is pivotally connected, and below this sleeve 89 the rod 88 has fixed thereon an abutment collar 90.

The portion of the rod 88 above the sleeve 89 is fitted telescopically and slidably within the lower end portion of a tube 91 that is supported in suitable bearings to move vertically. At opposite sides thereof the tube 91 is formed with longitudinal slots 92 occupied by studs 93 projecting from the rod 88. These slots equal to one-half of the total movement of the arm of lever 59 that is connected with sleeve 89.

Near its lower end the rod 88 is connected with a hand lever 94 that is fulcrumed at 95 on any suitable support, while the tube 91 has a similar hand lever 96 connected therewith fulcrumed at 97 on any suitable support. Stops 98 are provided to limit the swing of the lever 94 and stops 99 are provided to limit the swing of the lever 96.

The parts of this mechanism are shown in the positions they occupy when the car is at the limit 10 of its downward movement. At this time the arm 65 on the piston is against and beneath the abutment 86 so as to hold the collar 90 against the lower end of the sleeve 89 so as to hold lever 59 in its intermediate position, the upper end of 15 the sleeve 89 then being in engagement with the lower end of the tube 91 with the pins 93 at the upper ends of slots 92.

With the parts in these positions the lever 59 can be operated only by upward movement of the 20 rod 88 manually effected by means of the lower lever 94 and this upward movement of said rod acts through lever 59 to adjust the valve 46 so as to cause the car 38 to travel upwardly.

As the car 38 reaches the limit of its upward 25 movement, the arm 65 on the piston engages the abutment 87 on rod 88 and moves the latter downwardly, said rod acting through pins 93 and tube 91 to swing the valve-operating lever 59 back into its intermediate position shown in Fig. 30 7 thereby shutting off the supply of water to the cylinder and stopping the car.

While the car is at the limit of its upward movement the lever 59 can only be operated by 35 downward movement of tube 91 manually effected by means of the lever 96 since the arm 65 is then against abutment 87.

It will thus be clear that when the car 38 is at the limit of its downward travel only the lever 94 can be operated to start the car on its upward 40 travel and that when the car is at the limit of its upward movement only the lever 96 can be operated to start the car upon its downward travel.

It should also be clear that while the car is in motion, it can be stopped by either lever 94 or 45 96 which at such times can also be utilized to start the car in a direction away from the lever that is operated.

What I claim is:

1. In a building, the combination with the 50 gravity water service system thereof, of an elevator apparatus having, in combination, a vertically movable car; a hydraulic engine for operating said car disposed substantially below the level of the normal head of the water of said system so as to be operated thereby; a supply conduit through which water is delivered to said engine from the water service system of the building; valve means for controlling the passage of

water to and from said engine and with which one end of said supply conduit is connected; a check valve in said supply conduit which closes toward said water system; an auxiliary emergency accumulator tank that is automatically 5 loaded with a reserve supply of water from said water service system and a conduit connecting said accumulator tank with said first-mentioned supply conduit between said check valve and said valve means so that when the water pressure of 10 the water service system of the building falls below a predetermined point the engine is automatically supplied with water from said tank.

2. In a building, the combination with the gravity water service system thereof, of an elevator apparatus having, in combination, a vertically movable car; a hydraulic engine for operating said car disposed substantially below the level of the normal head of the water of said system so as to be operated thereby; a supply conduit through which water is delivered to said engine from the water service system of the building; valve means for controlling the passage of water to and from said engine and with which one end of said supply conduit is connected; a 15 check valve in said supply conduit which closes toward said water system; an air tight auxiliary emergency accumulator tank that is automatically loaded with a reserve supply of water from said water service system, and containing a body 20 of air under compression, and a conduit connecting said accumulator tank with said first-mentioned supply conduit between said check valve and said valve means, said tank occupying an elevated position adjacent to the level of the normal head of the water within said system.

3. In a hydraulic dumbwaiter apparatus of the character described, the combination with the valve means thereof, of mechanism for controlling and operating said valve means comprising 40 a manually operated member accessible to a person on a lower floor of the building; a manually operated member accessible to a person on an upper floor of said building, and means connecting said members with said valve means so that 45 operation of one member adjusts the other member and so that manual operation of either member while the car of the apparatus is at rest at the limit of its movement in either direction is effective only to start said car on its travel away 50 from the floor of the building where both it and said member are located.

4. An elevator apparatus constructed in accordance with claim 3 wherein each of said members is manually operable to stop the car while 55 the latter is in motion.

MARTIN B. McLAUTHLIN.
